UNITED STATES PATENT OFFICE.

WALTER T. GODDARD, OF VICTOR, NEW YORK, ASSIGNOR, BY MESNE ASSIGNMENTS, TO LOCKE INSULATOR CORPORATION, OF BALTIMORE, MARYLAND, A CORPORATION OF MARYLAND.

STRAIN CLAMP FOR ELECTRICAL CONDUCTORS.

Application filed December 8, 1917, Serial No. 206,207. Renewed January 15, 1923.

To all whom it may concern:

Be it known that I, WALTER T. GODDARD, a citizen of the United States, and a resident of Victor, in the county of Ontario and State 5 of New York, have invented certain new and useful Improvements in Strain Clamps for Electrical Conductors; and I do hereby declare the following to be a full, clear, and exact description of the same, reference being had to the accompanying drawings, 10 forming a part of this specification, and to the reference characters marked thereon.

The object of my invention is to improve the construction of strain clamps of the type 15 employed in connection with electrical conductors or cables, where they are attached either to a ground anchor or to a supporting pole. More particularly, the invention has for its purpose to lessen the cost of such a 20 clamp as well as to facilitate its operation. In a further aspect, the invention is designed to afford an extremely rigid clamp that will effectually prevent any slipping of a cable, after it is once positioned, and also make it 25 possible to assemble it readily in clamping relation. To these and other ends the invention consists in certain improvements and combinations of parts, all as will be herein- 30 after more fully described, the novel features being pointed out in the claims at the end of the specification.

In the drawings:

Figure 1 is a plan view of the blank from 35 which the clamp is made, according to my invention;

Figure 2 is a side elevation showing one form of the device with a cable clamped therein;

Figure 3 is a top plan view of the clamp 40 appearing in Figure 2;

Figure 4 is a side elevation of a modified form of the invention;

Figure 5 is a transverse sectional view on the line 5^a—5^a of Figure 2;

Figure 6 is a transverse sectional view on the line 6^a—6^a of Figure 2, and

Figure 7 is a transverse sectional view on the line 7^a—7^a of Figure 4.

Similar reference characters throughout 50 the several views indicate the same parts.

For the purpose of understanding the general operation and use of the device, it may be stated briefly that where a conducting cable is to be anchored either at one end or at some

point between the ends, the clamp is attached 55 at the point of anchorage, and the cable and clamp are drawn as taut as possible with the cable properly inserted within the clamp. While the parts are held in tightly stretched relation by a suitable temporary device the 60 clamping instrumentalities are applied to the clamp, with the result that the conductor is retained in the desired position against slippage.

The present device is made by stamping 65 out a blank such as shown in Figure 1, from pressed steel or other suitable metal, and bending it upon itself along a longitudinal central line, forming opposite clamping walls or jaws which are subjected to additional stamping or pressing operations to impart the required contour. Referring to Figures 1 to 3, 5 and 6, the opposite walls are designated by 1 and 1^a, and are provided with bolt openings 2 and 2^a which receive the 70 clamping devices or bolts 3. The clamping devices consist of bolt heads 3^a and nuts 3^b, the inner faces of which are of spherical formation and engage inwardly flared portions or seats 4 and 4^a of the opposite walls of the 75 clamp. Arranged beyond these inwardly flared portions are outwardly flared portions 5 and 5^a, forming seats for the cable or conductor 6. The opposite walls terminate in outwardly flaring edges 7 and 7^a which 80 permit of readily inserting the cable 6 when the clamping devices are loosened. After the conductor is positioned in the clamp, the clamping nuts are tightened on the bolts and through their cooperation with the inwardly 85 flared portions referred to, exert sufficient pressure upon the clamping walls to rigidly hold the conductor against slippage between the outwardly flared portions 5 and 5^a. The 90 bolt openings in the wall 4^a are square, and receive cooperating squared shoulders 8 on the bolts, preventing the latter from turning in the clamp.

In some cases it may be desirable to secure 95 greater clamping action, owing to larger 100 sized conductors or to a possibility of abnormal strain, and to take care of such a condition, I have provided the modified arrangement illustrated in Figures 4 and 7 and including a double set of clamping instrumentalities, one on each side of the conductor. In this form the wall 9 is provided 105 with bolt openings 10, which extend from

its free edge inwardly and thus permit a bolt to be removed from the wall without disengaging its nut. The opposite wall 11 has a curved edge portion 11^a extended beyond the free edge of the wall 9, and its bolt openings 12 extend from a point adjacent to its free edge inwardly to a point substantially opposite the inner extremities of the bolt openings in the wall 9. With this arrangement, the outermost clamping devices or bolts 13 can be moved outwardly to the position shown in dotted lines in Figure 7 when the nuts 14 are loosened. The bolts are then held by the extended portion of the wall 11 and are disengaged from the opposite wall 9, thus permitting the conductor to be inserted into its seat, after which the clamping bolts 13 are moved inwardly to the position shown in full lines in Figure 7, and the clamping nuts are tightened. The walls 9 and 11 embody curved portions 15 and 16 which constitute seats for the outermost clamping devices, while the inner clamping devices engage curved seats as in the form first described.

Arranged between the clamping devices are transverse ribs formed by the inwardly pressed portions 4^a which form ribs that strengthen and brace the clamp, giving it sufficient stiffness to prevent bending or buckling under excessive strain. The portion of the blank connecting the opposite walls is preferably cut away at 18, while the ends 19 are connected by a narrow, integral strip 20. Said ends 19 are also provided with openings 21 which are surrounded by integral inwardly projecting collars 22, preferably abutting one another at their adjacent edges and forming engaging devices or bearings for a connecting pin by which the clamp is attached to an insulator or other anchor. The opposite ends of the walls also have engaging devices or eyes 23 by which connection can be made to the clamp during the operation of stretching the conductor preliminarily to securing it. The numerals 24 designate oppositely disposed arcuate slots or openings in the walls of the clamp to receive a bolt 25 and cooperating nut 26. The bolt 25 is adjustable within said slots 24 in order to vary the angle or curve which the free portion 27 of the cable makes with the clamped portion 6. This is used where a cable is clamped or anchored to a supporting pole at a point between the ends of the cable, the portion 27 constituting part of the loop which extends around the insulator to which the conductor is attached. As it may be desirable to increase or diminish the size of this loop in accordance with the size of the insulator and also of the conductor, this can be definitely established by adjusting the bolt 25. 28 designates a slot or recess preferably formed by inwardly pressed ribs in the sides of the

clamp to receive an arcing arm that is held in place by a cooperating bolt 29.

I claim as my invention:

1. A strain clamp for electrical conducting cables consisting of an integral blank bent upon itself affording opposite clamping walls in spaced relation to each other, one of said walls having bolt openings extending inwardly from its free edge, and the other of said walls being wider than the first named wall and having elongated bolt openings extending from a point adjacent to its free edge to a point substantially opposite the inner extremities of the openings in the other wall. 75

2. A strain clamp for electrical conducting cables consisting of an integral blank bent upon itself affording opposite clamping walls in spaced relation to each other and having openings to receive bolts for drawing the walls into clamping relationship with an interposed cable, said walls having outwardly flared portions forming a seat for a conductor and inwardly flared portions forming seats for clamping devices. 85

3. A strain clamp for electrical conducting cables consisting of an integral blank bent upon itself affording opposite clamping walls in spaced relation to each other, one of said walls having bolt openings extending inwardly from its free edge, and the other of said walls being wider than the first named wall and having elongated bolt openings extending from a point adjacent to its free edge to a point substantially opposite the inner extremities of the openings in the other wall; both of the walls having outwardly flared portions forming a seat for a conductor and inwardly flared portions forming seats for clamping devices. 95

4. A strain clamp for electrical conducting cables consisting of an integral blank bent upon itself affording opposite clamping walls in spaced relation to each other, one of said walls having bolt openings extending inwardly from its free edge, and the other of said walls having an extended curved edge portion and elongated bolt openings extending from a point adjacent to its free edge to a point substantially opposite the inner extremities of the openings in the other wall. 100

5. A strain clamp for electrical conducting cables consisting of an integral blank bent upon itself affording opposite clamping walls in spaced relation to each other, one of said walls having bolt openings extending inwardly from its free edge, and the other of said walls having an extended curved edge portion and elongated bolt openings extending from a point adjacent to its free edge to a point substantially opposite the inner extremities of the openings in the other wall, both of the walls having 110

outwardly flared portions forming a seat for a conductor and inwardly flared portions forming seats for clamping devices.

6. A strain clamp for electrical conducting cables consisting of an integral blank bent upon itself affording opposite clamping walls in spaced relation to each other, said walls having oppositely arranged eyes at one end and openings at the opposite 10 end surrounded by inwardly projecting integral collars forming a bearing for a pin connection.

7. A strain clamp for electrical conducting cables consisting of an integral blank bent upon itself affording opposite clamping walls in spaced relation to each other, the walls having outwardly flared portions forming a seat for the conductor, inwardly flared portions with bolt openings therein 15 arranged on one side of said seat and forming seats for clamping devices, and flat portions with bolt holes therein on the other side of the conductor seat forming seats for outermost clamping devices.

20 8. A strain clamp for electrical conducting cables consisting of an integral blank bent upon itself affording opposite clamp-

ing walls in spaced relation to each other, the walls having outwardly flared portions forming a seat for a conductor, inwardly flared portions with bolt openings therein 30 arranged on one side of said seat and forming seats for clamping devices, flat portions with bolt openings therein on the other side of the conductor seat forming 35 seats for outermost clamping devices, and an extended curved edge portion on one of the walls having elongated bolt openings extending from a point adjacent to its outer edge to a point substantially opposite the 40 inner extremities of the cooperating openings in the other wall.

9. A strain clamp for electrical conducting cables consisting of an integral blank bent upon itself to afford opposite clamping walls in spaced relation to each other, clamping devices to draw the walls into 45 clamping relationship with an interposed cable, transversely extending ribs for strengthening the clamping walls, and engaging devices at the ends of the clamp for 50 the attachment of cable stretching means.

WALTER T. GODDARD.
